UNITED STATES PATENT OFFICE.

STEPHEN B. TOLSON AND ANDREW SCHOPP, OF BELLEVILLE, ILLINOIS, AS-SIGNORS TO THE SUCKER STATE DRILL COMPANY, OF SAME PLACE.

DISK ATTACHMENT FOR GRAIN-DRILLS.

SPECIFICATION forming part of Letters Patent No. 654,037, dated July 17, 1900.

Application filed March 29, 1900. Serial No. 10,590. (No model.)

To all whom it may concern:

Be it known that we, STEPHEN B. TOLSON and ANDREW SCHOPP, citizens of the United States, and residents of Belleville, in the 5 county of St. Clair and State of Illinois, have invented certain new and useful Improvements in Disk Attachments for Grain-Drills, &c., of which the following is a full, clear, and exact description, reference being had to the 10 accompanying drawings, forming part of this specification.

Our invention relates to a novel manner of mounting ground-working disks that are used in connection with grain-drill shoes, as shown, 15 or independently thereof, our object being to so mount the disks as to afford for their adjustment to any desired angle relative to the drag-bar, while they will be rigidly held at any angle to which they may be placed.

20 Our invention consists in features of novelty hereinafter fully described, and pointed out in the claims.

Figure I is a perspective view illustrative of our invention. Fig. II is a top or plan view. Fig. III is an enlarged view of the box or housing by which the disk and shoe are attached to the drag-bar. Fig. IV is an enlarged vertical section taken on line IV IV, Fig. II. Fig. V is an enlarged vertical section on line V V, Fig. I. Fig. VI is a horizontal section on line VI VI, Fig. V. Fig. VII is a detail perspective view showing the inner end of the arm of the shoe that is attached to the drag-bar. Fig. VIII is a side elevation. Fig. IX is a section on line IX IX, Fig. VIII.

Referring to the drawings, 1 represents a drag-bar, which may (with a number of mates) be made fast to the frame of a grain-drill by means of a rod 2.

3 is one of the shoes of a grain-drill, made hollow, as usual, to receive one of the feed-tubes. (Not shown.) The shoe has an inwardly-extending portion 4 cast thereon, (see Fig. IV,) to which one end of a sleeve or tube 5 is held by a bolt 6. The sleeve or tube 5 forms the journal for the hub 7 of the disk 8, the hub being held from outward movement on the journal by a shoulder or flange 9 on 45 the outer end of the journal.

50 10 represents a box or housing inclosing the

hub 7 and provided with an oil-hole 11. Between the hub and the box there is an oil-space 12. The outer end of the box bears against the periphery of the flange 9, and its 55 inner end bears against a shoulder 13 on the hub 7.

The box or housing 10 is provided with an arm 14, that is pivoted to the drag-bar by a bolt or pin 15 and having also a slot-and-bolt 60 connection 16 with the drag-bar. The box or housing thus serves to connect the disk to the drag-bar, and by loosening on the bolt 16 the disk can be adjusted to any desired angle, as shown by full and dotted lines, Fig. 65 II, and then by tightening the bolt the disk is held to whatever angle it may be adjusted. To avoid any possibility of the disk moving from its adjustment when at work, the shoe 3 is provided with an arm 17, that has a slot- 70 and-bolt connection 18 with the drag-bar, the adjustment being made here at the same time as the adjustment of the arm 14. There is a connection thus made between the drag-bar and the disk on both sides of the latter— 75 by the box 10 and its arm 14 on one side and by the shoe 3 and its arm 17 on the other side— so that the disk cannot possibly move from its adjustment.

20 represents a scraper for cleaning the 80 disk, the arm 21 of which is made fast to the shoe 3 by a slot-and-bolt connection 22. (See Figs. I, V, and VI.) It is important that this scraper be so arranged that it can be efficiently and quickly adjusted to the disk as 85 it becomes worn. This we accomplish by forming a concavo-convex bearing 23 between the shoe and the arm of the scraper, as shown in Fig. V, so that when the bolt 22 is loosened and the arm moved downwardly the scraper 90 will naturally be moved inwardly against the disk.

The scraper cleans one side of the disk as it comes out of the ground, and to clean the other side of the disk we form the shoe with 95 an inturned edge 24, (see Figs. VIII and IX,) that scrapes against the disk and cleans it as it comes out of the ground.

We claim as our invention—

1. The combination of a drag-bar, a disk 100 pivoted to the bar, a shoe to which the disk is journaled, and an arm on the shoe and

which is adjustably connected to said bar, substantially as set forth.

2. The combination of a drag-bar, a disk, a box inclosing the journal of the disk and provided with a lug that is pivoted to the bar and has a bolt connection therewith, and a shoe to which the disk is journaled and which is provided with an arm having a slot-and-bolt connection with said bar, substantially as set forth.

3. The combination of a drag-bar, a shoe having an arm adjustably connected to said bar, a journal connected to said shoe, a disk having a hub fitting over said journal and a box inclosing said hub and having an arm that is pivoted to said bar and has also a slot-

and-bolt connection therewith, substantially as set forth.

4. The combination of a disk, a shoe to which the disk is journaled, and a scraper adapted to bear against the disk and having an arm that is connected to said shoe by a bolt-and-slot connection; said arm having a concavo-convex bearing against the shoe, substantially as and for the purpose set forth. 25

In testimony whereof we have hereunto set our hands this 26th day of February, 1900.

STEPHEN B. TOLSON.
ANDREW SCHOPP.

In presence of—

WALTER E. LIESE,
WILLIAM WEIDMANN.
